UNITED STATES PATENT OFFICE.

CHARLES NETTER, OF NEW YORK, N. Y.

METALLIC RAILROAD-TIE.

SPECIFICATION forming part of Letters Patent No. 372,864, dated November 8, 1887.

Application filed August 8, 1887. Serial No. 246,430. (No model.)

To all whom it may concern:

Be it known that I, CHARLES NETTER, of the city, county, and State of New York, have invented a certain new and useful Improvement 5 in Metallic Railway-Ties, of which the following is a specification.

The object of my improvement is to provide a railway-tie, to be made of iron or steel, whereby much greater economy, with stability, 10 is obtainable than usual.

I will first describe in detail a railway-tie embodying my improvement, and then point out the various features of the said improvement in claims.

15 Reference is to be had to the accompanying drawings, forming a part of this specification, in which similar letters of reference indicate corresponding parts in all the figures.

Figure 1 is a plan view illustrating railway-ties embodying my improvement laid, and supporting rails. Fig. 2 is a vertical section across the track on the line *x x*, Fig. 1. Fig. 3 is a vertical section taken longitudinally of the track on the line *y y*, Fig. 2.

25 The tie A comprises a straight top plate, B, a little longer than the width of the track, plates C, depending at right angles from both ends of the top plate, and extension-plates D, projecting outward from the lower ends of 30 both the depending plates C in a plane parallel with the top plate, and a continuous flange, E, depending centrally from and extending along the under side of the top plate, B, end plates, C, and extension-plates D.

35 This tie will generally be made by rolling the iron or steel into the form of a straight bar having the T-section, clearly shown in Fig. 3, the flange E forming the shank of the "T," and by then bending it, by any of the 40 well-known means for accomplishing that object, into the peculiar form described.

The tie A is buried, so as to bring the top plate, B, on the surface of the track-bed, as shown in Figs. 2 and 3. The top plate will then anchor the tie against sinking, the 45 vertical end plates, C, against endwise movement, the buried extension-plates D against lifting, and the longitudinal flange E against movement longitudinally of the track-bed, while also acting as a rib to stiffen the tie 50 lengthwise against flexure.

I prefer to fasten the rail to the tie A by passing a hook-bolt, F, through an aperture, G, formed in the top plate, B, adjacent to the flange E, slipping the hooked end of the bolt 55 over the lower edge of said flange, and drawing an ordinary clip-plate, H, down upon the base of the rail by means of a nut, I, screwing on the upper end of the bolt. Expansion and contraction of the rails is thus not interfered 60 with, while all lateral deflection is prevented.

I claim as new and desire to secure by Letters Patent—

1. A metallic railway-tie comprising a straight top plate, depending end plates, C, 65 extension-plates D, projecting outward from the lower ends of the depending end plate, and a stiffening and anchor flange, E, depending from and extending centrally along the under side of the said top and extension plates, 70 substantially as described.

2. As an improved article of manufacture, a metallic railway-tie formed of a single T-bar bent downward at right angles toward the shank of the T at the ends and then oppositely 75 outward at right angles, substantially as described.

CHARLES NETTER.
